UNITED STATES PATENT OFFICE

2,539,884

FLUID PUMPING FILM REEL

Robert M. Barth, Pelham Manor, N. Y., assignor
to the FR Corporation, New York, N. Y., a
corporation of New York

Application December 1, 1949, Serial No. 130,427

3 Claims. (Cl. 95—90.5)

1

The present invention relates generally to the art of photography. In particular it relates to the art of and apparatus for processing photographic or other film by subjecting same to the action of chemicals in fluid state. Even more particularly, the present invention relates to the apparatus wherein photographic film is disposed during processing by suitable fluids of the type including a film supporting reel shown, for example, in Naylor and Fink U. S. Patent No. 2,298,963.

Experience has shown that it is highly desirable in the development of photographic film to agitate the same during the period of immersion thereof in the developing fluid. Proper agitation during such immersion makes for evenness in the processing, if the entire area of the film is contacted by the processing fluids. Proper agitation also removes air bubbles on the film surface, thereby eliminating spots and the like. This agitation has been accomplished in previous constructions either by whirling the reel supporting the film within the tank or by rocking the tank on a suitable support. These, however, are haphazard methods, reflected in streaks and unevenly exposed areas. So far as is presently known, there is no device which functions positively to direct the fluids forcefully through the film convolutions so as to ensure contact of the entire area of the film being treated.

The main object of the present invention, therefore, is the provision of a film tank comprising a casing having a rotatable film supporting reel therewithin, on which reel the film is wound in spaced convolutions, or otherwise held in spaced relation, rotation of which reel causes a positive and direct movement of the processing fluids within the tank across the entire surface of the film being processed.

Another object of the present invention is in the provision of a device of the character described, wherein the film supporting reel is formed of a pair of spaced discs, each including a plurality of radially extending ribs, the upper and lower surfaces of which ribs are angled from the horizontal so that on rotation of the reel, a pumping action will be developed by the movement of the angled faces through the processing fluid.

With the device of my invention, a turbine effect is developed upon rotation of the reel within the tank whereby the rib portions of the reel will pump or force the fluid into and between the film convolutions, as a result of which the entire surface of the film will be contacted by and sub-

2

jected to the action of the film processing fluids. Other, further and more specific objects of the present invention will in part be obvious and in part pointed out specifically in the following description of an illustrative embodiment.

In the drawings annexed hereto and forming a part hereof,

Figure 1 is a vertical section through one form of device constructed according to and embodying my invention;

Figure 2 is a plan view of a disc component;

Figure 3 is a section on the line 3—3 of Figure 2;

Figure 4 is a section on the line 4—4 of Figure 2; and

Figure 5 is a perspective view, from the underside, of a portion of the reel disc, partly broken away.

The reel of my invention is indicated generally 20 by reference numeral 10, and comprises a pair of circular discs 12, 12. In use, discs 12, 12 are spaced apart in parallel relationship on a shaft 14, and maintained in a predetermined relative position by any suitable means. If desired, one 25 of the discs may be formed as an integral part of the shaft 14, as is conventional in the art.

Each disc 12, formed as by molding, stamping otherwise, of plastic material or the like, comprises a circular outer ring 18, a film entrance opening 20 thereinto, and a helical wall 22, coiling inwardly from the periphery of the disc, adjacent opening 20, to a point adjacent the apertured centrally disposed core 26. Core 26 is apertured, as at 24. The convolutions of wall 22 define a helical film receiving groove or path 28. The helically winding wall 22 is supported from the underside thereof by a plurality of radial ribs or vanes 30, 30, extending from outer ring 18 to core 26. In addition, a number of shorter supporting ribs or vanes 32, 32 may be provided, reaching from outer ring 18 to a point short of core 26.

In the embodiment shown in Figure 2, eight full ribs or vanes 30, 30 are provided, with eight 45 stub ribs or vanes 32, 32, the full and stub ribs being alternately placed, thereby providing openings as 40, 40 between the convolutions of wall 22 adjacent ring 18, and openings 42, 42 adjacent core 26 for the free passage of fluid through the disc.

Referring now to Figures 3 and 5, each of ribs 30, 32 is formed, in section, as an elongated member, the upper and lower sides 50, 50 of which are angled from the horizontal. The degree of angularity need be of such order as to develop a posi-

tive driving movement of the fluid, and I have found, for example, that an angularity of 18° is quite satisfactory. The invention, however, is not to be so limited, except by the appended claims. When a pair of discs 12, 12 are spaced apart on support, as 14, with openings 28, 28 in alignment, a film strip 60 may be threaded into the reel thus formed, either by attachment to the shaft 14 or cores 26, 26, and thence around film path 28 to the outer portion of the reel, or the film may be pushed into the reel from opening 20 thence inwardly along path 23 until the end of the film is inserted in stop pocket 62. When the film is inserted in the reel, with the disc of Figure 2 as the lower one and a disc of opposite curvature in respect of wall 22, the leading end of the strip will ride up the inclined top sides 50, 50, of the first ribs 39a and thereafter slide inwardly between the opposed discs around the helical path 26. As seen in Figure 1, the walls 22, 22 define opposing and aligned pathways 28, 28, spacing apart the necessary convolutions of the film. In Figures 3, 4 and 5, it will be seen that portions of the ribs project up into the film receiving path.

When the film-loaded reel is then disposed within a suitable container or tank shell, as 70, and immersed in the processing fluid disposed therewithin, all parts of the film will, or should normally, be contacted by the said fluid. With the reel constructed as above described, on clockwise rotation of the reel, via actuation of shaft 14, the angled upper faces 50, 50 of ribs 38, 32 will move the fluid, and force same upwardly through openings 40, 42 thereby ensuring a positive directed movement and turbulation of the fluids against all surfaces of the film. When rotated counterclockwise, the lower angled faces of ribs 39, 32 will force the fluid downwardly against the bottom of the container 70 and thence upwardly through openings 40, 42, securing the same directed and positive movement of the processing fluids. Rotated in either direction, my

reel will develop a positive movement of the processing fluid directing and forcing the fluid between the spaced film convolutions.

Having described my invention, what I claim and desire to secure by Letters Patent is:

- 5 1. A film supporting reel including a centrally disposed shaft, a pair of circular discs thereon spaced apart along the length of the shaft, a continuous helical wall on each disc extending around the disc from a point adjacent the center of the disc to a point on the periphery of the disc, the wall convolutions of one disc opposing the wall convolutions of the other disc defining a film receiving and retaining trackway, and means on the discs to support the convolutions of the continuous wall, which means comprise a plurality of ribs integral with the wall on the outer aspects of the discs extending axially thereof, the upper and lower surfaces of the ribs being angled with respect to the planes of the discs.
- 10 2. A film supporting reel as in claim 1, in which only certain of the ribs extend the full distance from the outer periphery of the disc to the inner margin thereof.
- 15 3. A film supporting reel as in claim 1, in which the angled ribs project into and between the wall convolutions but to a point spaced inwardly of the tops of the walls.
